CLAIM

The ornamental design for an automated teller machine, as shown and described.

DESCRIPTION

FIG. 1 is a front, top perspective view of an automated teller machine, showing our new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
FIG. 7 is a bottom plan view thereof.

The inner rectangular panel adjacent to the headphone symbol and circular button panel is shown in broken lines and forms no part of the claimed design.

The dashed-dot lines in FIGS. 1-7 represent a boundary line and form no part of the claimed design. The even dashed lines represent unclaimed subject matter and form no part of the claimed design.
